UNITED STATES PATENT OFFICE.

THOMAS MERCER, OF PRESTON, ENGLAND.

CRANK MANUFACTURE.

1,022,434.

Specification of Letters Patent.

Patented Apr. 9, 1912.

Application filed March 17, 1910. Serial No. 550,039.

To all whom it may concern:

Be it known that I, THOMAS MERCER, subject of the King of England, residing at Frank street, off North Road, Preston, in 5 the county of Lancaster, England, have invented certain new and useful Improvements in Crank Manufacture, of which the following is a specification.

This invention relates to the manufacture 10 of crank shafts, and has for its object to provide a crank which is stronger than those previously made.

According to this invention a blank of approximately the same thickness as the 15 completed crank shaft and having a widened portion where the crank is to be made, is forged or otherwise formed, the breadth of the widened portion being substantially equal to the throw the crank is eventually 20 to have. The ends of the bar on either side of the widened portion are forged or drawn out to the required length and a hollow is preferably formed in the upper edge of the widened portion. The blank thus formed 25 is then reheated and subjected to pressure between suitable dies which are so shaped that the complete crank is formed in one operation when they are forced together.

The dies or blocks are in shape similar to 30 those already used for forging bent cranks from a rod of uniform diameter, being of such form that when brought together they inclose a space corresponding in shape to a completed crank shaft, the coöperating surfaces of the dies being provided with semi-cylindrical grooves whereby the crank pin and crank shaft are formed. In some cases the semi-cylindrical groove may be extended 35 along those surfaces of the dies which form 40 the web of the crank, or the dies may be so shaped that a web of rectangular or other cross-section is formed if desired.

A crank shaft made in accordance with the above method has its angle formed 45 square, differing in that respect from the rounded corners of the usual bent crank. A greater thickness of metal is thus obtained where strength is most required.

In the accompanying drawings, Figure 1 50 shows in side elevation a blank from which a completed crank shaft is to be made. Fig. 2 shows in side and end elevation, by way of example, a pair of dies in accordance

with this invention the upper die being shown in its raised position, and Fig. 3 is 55 a view similar to Fig. 2 showing the dies in their closed position.

To impart the final form to the crank shaft the apparatus employed comprises an upper block A having two projecting guides 60 or shoulders A' formed on its face, and a hole or recess A² for the introduction of a bar or tool enabling the block to be readily handled. The under or operative surface of the block A is hollowed to coincide with 65 the shape of the inner surface of the finished crank shaft, a semi-cylindrical groove A³ being provided along the whole length of its operative surface. If desired, however, a groove of other cross-section may be provided along the vertical portion of the block 70 A should it be desired to form a crank having a web of rectangular or other cross-section.

The lower die comprises two blocks B 75 bolted together between plates D, a distance piece or block C being interposed between the blocks B but only held in place by friction, so that this central block can be displaced to facilitate the removal of the finished crank shaft after stamping. The blocks B are provided with grooves B' similar to those in the block A, and the central block is also grooved as at C' on its upper surface, the ends C² being shaped to fit that 80 portion of the groove B' which is formed on the inner vertical edges of the blocks B. The blocks B are conveniently provided 85 with recesses, such as B², for the insertion of tools or bars to facilitate handling. Downward slots are formed in the plates D into 90 which the shoulders A' on the block A enter and thus guide the upper block in its descent.

Figs. 2 and 3 show in dotted lines the 95 blank and finished crank respectively.

What I claim as my invention and desire to secure by Letters Patent is:—

The herein described method of making crank shafts consisting in forming a blank 100 with end sections of a thickness approximately the same as the completed shaft and an intermediate section of greater thickness from which the crank is formed, said intermediate section having a recess in its upper 105 edge between the portions thereof adapted

to constitute the angles connecting the shaft sections and crank in the finished article, heating said blank and then forging it by pressure between dies so shaped that a complete crank shaft having its shaft and crank sections connected by square angles is formed at one operation.

In testimony whereof I have signed my name to this specification in the presence of two subscribing witnesses.

THOMAS MERCER.
